Primary Examiner — Sandra S Snapp*Assistant Examiner* — Ieisha N Price(74) *Attorney, Agent, or Firm* — Capitol City TechLaw(57) **CLAIM**

The ornamental design for a nut, as shown and described.

DESCRIPTION

FIG. 1 is a top perspective view of a nut showing my new design;

FIG. 2 is a front view thereof, the rear view being a mirror image thereof;

FIG. 3 is a left side view thereof, the right side view being a mirror image thereof;

FIG. 4 is a top view thereof; and,

FIG. 5 is a bottom view thereof.

The dashed broken lines shown in the figures illustrate portions of the nut that form no part of the claimed design.

1 Claim, 5 Drawing Sheets(56)
